DES. 2006

Letters Patent No. 2006 - Dated Decr 13 - 1864.

Design for a Book's Stove.

Des. 2006

The schedule referred to in these Letters Patent and making part of the same.

Wall whom it may concern:

Be it known that I, Edmund J. Bridge, of the City of Troy, in the County of Rensselaer and State of New York, have invented or produced a certain new and original design for an "Elevated oven Book Stove," and I do hereby declare that the following is a full and exact description of the same, reference being had to the accompanying perspective drawing, and to the letters of reference marked thereon forming part of this specification which was as follows: A. A. A. are panels upon the oven front plate, and have convex shaped surfaces, divided into squares by grooves running diagonally across the surface, and the faces of said squares are grooved or recessed by two grooves crossing each other at right angles and forming across in the central surface of said squares in the manner as shown in the accompanying drawing. B. B. B. are mouldings surrounding the above described panels. C. is the oven door having a convex or raised panel D. of the same ornamental design as the panels A. A. A. and surrounded by the moulding E. E. is the end fire door and G. G. the front sliding fire doors, having panels of the same design as the panels A. A. A. and surrounded with mouldings H. H. H. I. is the bottom plate with the mouldings I. K. is the top plate with the mouldings I. M. is
